Primary Examiner — Zenia I Bennett

(74) Attorney, Agent, or Firm — Kevin Keener; Stephen Presutti

(57) **CLAIM**

The ornamental design for an eyeliner stencil, as shown and described.

DESCRIPTION

FIG. 1 is a perspective view of an eyeliner stencil showing my new design;

FIG. 2 is a front view of the eyeliner stencil;

FIG. 3 is a rear view of the eyeliner stencil;

FIG. 4 is a left side view of the eyeliner stencil;

FIG. 5 is a right side view of the eyeliner stencil;

FIG. 6 is a top plan view of the eyeliner stencil;

FIG. 7 is a bottom plan view of the eyeliner stencil;

FIG. 8 is a perspective view of the eyeliner stencil showing the eyeliner stencil from the liner; and,

FIG. 9 is a perspective view of the eyeliner stencil separated from the liner.

The broken lines in the drawing depicting portions of the eyeliner stencil and the fingers shown in FIG. 8 are for illustrative purposes only and form no part of the claimed design.

1 Claim, 6 Drawing Sheets(56)
